UNITED STATES PATENT OFFICE

EDWARD ROSS, OF LAWRENCE, MASSACHUSETTS, ASSIGNOR TO DRAPER CORPORATION,
OF HOPEDALE, MASSACHUSETTS, A CORPORATION OF MAINE

LOOM SHUTTLE

Application filed September 13, 1932. Serial No. 632,961.

The present invention relates to automatically threading shuttles for filling replenishing looms.

Shuttles of the type mentioned usually include a shuttle body having means for supporting a filling carrier, and an automatically threading eye which, in many instances, carries a friction device for tensioning the running filling. At the time of replenishment, the filling leading from the shuttle to the selvage of the cloth being woven is cut in a manner to leave a trailing end projecting from the shuttle eye before the filling carrier is ejected and replaced by a fresh one. This 10 ejection of the filling carrier is intended to withdraw the trailing end of filling through the shuttle eye and thus remove it from the influence of the weaving instrumentalities. However, the tension device tends to prevent this withdrawal of the filling end, and frequently the filling merely unwinds from the filling carrier, or breaks between the shuttle eye and the filling carrier, thus leaving the trailing end in the shuttle eye, from whence it may be carried into the shed and woven into the cloth or become entangled with and break the running filling.

It has been heretofore proposed to release the outgoing filling end from the tension device by opening the tension at time of transfer by means of levers, wedges, etc. adapted to physically engage and separate the tension members. Such a means for overcoming the difficulties mentioned is not a practical 30 solution of the problem involved as it necessitates the addition of a considerable number of parts to the transfer mechanism, already somewhat complex in construction and operation. I propose to release the filling from the tension device by manipulating the filling itself, rather than the tension device.

It is accordingly the principal object of my invention to provide, in an automatically threading loom shuttle, a filling tension device and means cooperating therewith for automatically removing the outgoing filling laterally from the tension device at the time of transfer.

A further object of my invention is to provide a novel form of thread tension device,

particularly adapted for use with the aforementioned releasing means.

A still further object is to so construct and mount the tension device that it will serve as a slack take-up device to take up 55 slack in the running filling outside the shuttle.

Further objects of my invention will, in part, be hereinafter more specifically enumerated, and will, in part, become obvious 60 as the description proceeds.

Referring to the drawings, which illustrate the preferred embodiment of my invention:

Figure 1 is a plan view of a complete shuttle constructed in accordance with my invention;

Figure 2 is a front elevation of the same;

Figure 3 is a fragmentary plan of the eye end of the shuttle, drawn full size and showing the path of the filling at the beginning of the first pick after transfer;

Figure 4 is a view similar to Figure 3 but showing the filling fully threaded into the eye;

Figure 5 is a perspective view of the eye end of the shuttle, showing the path of the filling at the instant the filling carrier is being ejected from the shuttle;

Figure 6 is an elevation of the threading 80 block alone, showing back side thereof;

Figure 7 is an end elevation from the inner end of the threading block; and

Figure 8 is a front elevation of the threading block.

The shuttle herein disclosed is comprised of a shuttle body 1 having, adjacent one end thereof, a so-called shuttle spring 2 adapted to grip and hold the rings 3 on the butt of a bobbin 5 or other suitable filling carrier, the latter being located within the shuttle body, in a hollowed out portion 6. The manner of holding the filling carrier permits it to be automatically ejected and replaced by a fresh one whenever the filling supply thereon becomes substantially depleted, as is usual in shuttles designed for use with automatic filling replenishing looms.

A threading block, indicated generally at 7, is positioned in a recess 8 in the shuttle 100

body substantially in axial alignment with the filling carrier, and the longitudinal slot 9 in the block communicates at its outer end with a side delivery eye 10. At the juncture 5 of the slot 9 and the passage leading to the side delivery eye 10 is positioned a cylindrical post 11 for guiding the filling when the latter is fully threaded into the side delivery eye. Substantially above the post 11 is a 10 rearwardly and downwardly curved guard or horn 12 for preventing the filling from becoming unthreaded from the threading block. The threading block 7 may be retained in the recess 8 in the shuttle by means 15 of a bolt or screw 13.

The shuttle as thus far described, including the portions of the threading block above referred to, is not new, and may be of any suitable usual construction, the particular 20 construction shown being but arbitrarily selected to form, together with the parts hereinafter described, a complete, operative shuttle.

In accordance with my invention, the shuttle 25 is provided with a novel form of automatically threading tension device, which is also so constructed and mounted as to serve as a slack take-up device for taking up a limited amount of slack in the running filling 30 outside the shuttle. The shuttle is also provided with means operable upon ejection of the filling carrier to remove the running filling laterally of the tension, or take-up, device.

35 The friction device is comprised of a pair of opposed friction plates, yieldingly pressed together and carrying guides for guiding the filling therebetween on the first pick after transfer. The lower friction plate 14 is positioned horizontally and extends laterally of the running filling *f*, which normally passes over this plate. The plate 14, is provided at its forward edge with a pair of upstanding flanges 15 and 16 which have their 40 opposed edges downwardly curved as at 17 and 18 respectively to form opposed guides for guiding the filling into an aperture 19 in the plate.

The second friction plate 20 (see Fig. 8) 50 is positioned directly over the plate 14, and is provided with an upstanding flange 21 extending parallel to but spaced from the flange 16 on the first plate, for a purpose to be hereinafter described. Soldered or otherwise suitably secured to the upper friction plate 20 is a guide member 22 presenting a downwardly and rearwardly inclined guiding surface cooperating with the guide edges 17 and 18 to guide the filling, on the first 55 pick after transfer, to its normal running position, in which it extends between the friction plates and down through the aperture 19. Plate 20 is co-extensive, in plan, with guide 22.

60 65 The plates 14 and 20 are apertured to re-

ceive a pin 23, which is rotatably mounted in a bearing 24 in the threading block. The pin is headed over at its lower end, as at 25, Fig. 8, and is provided with an elongated nut or shoulder 26 just above the bearing 24. 70 The headed portion 25 and shoulder 26 prevent axial movement of the pin, while still permitting it to rotate freely. The friction plates 14, 20 rest directly on shoulder 26 and are retained thereagainst by a compression 75 spring 27 which surrounds pin 23 and bears against the upper friction plate 20.

The spring 27 is held under compression by means of a nut 28 threaded onto the upper end of pin 23. The nut 28 is engaged on 80 opposite sides by the flanges 16 and 21 on the friction plates. The flanges prevent the nut from turning and, when pin 23 is manually rotated as by means of a screw driver 85 the nut will move up or down axially of the pin. Adjustment of the nut by this means will serve to vary the force exerted by the spring and thus vary the frictional grip exerted by the plates 14, 20 on the filling. For 90 normal operating conditions the tension device should, of course, be so adjusted that the slip-grip exerted thereby is just sufficient to properly tension the filling as it runs between the plates.

The form of tension device described lends 95 itself readily to use as a slack take-up device. That is, the two friction members (plates 14, 20) are mounted on pin 23 in such manner as to be capable of a pivotal movement about the axis of the pin. Instead 100 of restraining this pivotal movement I prefer to leave the friction members free, and to adapt them to the said taking-up action. Accordingly, a coil spring 29 (Fig. 8) has one 105 end engaged in an aperture in flange 16 and its other end suitably fixed to the base of the threading block. This spring is biased in such a direction as to tend to move the friction members in a counter-clockwise direction, Figs. 3, 4 and 5, i. e. toward the filling carrier. However, the slip-grip exerted by the friction members on the filling is sufficient to overcome the effect of spring 29, and while the shuttle is in motion and the filling is tight the take-up device will 110 occupy the position shown in Fig. 4. Then, whenever the filling outside the shuttle becomes slack the friction members will tend to move toward the filling carrier to take up the slack. While the amount of slack in the filling that this device can compensate for is limited, the device will, nevertheless, compensate for the small variations in tension resulting from uneven filling, and will also serve to maintain the tension during that 115 interval between the boxing of the shuttle and the beating in of the filling.

The above mentioned means for automatically removing the outgoing filling end laterally from the tension and take-up device 120

may assume many forms. Herein it is constituted simply by a guide pin 30 positioned between the tension device and the filling carrier. The threading block is provided with

5 a curved hook or guard 31 of more or less conventional outline and the guide pin 30 may conveniently be attached thereto, as by soldering or otherwise. The guide pin, as more clearly shown in Figs. 5 and 7, extends
10 from a point adjacent the top of the front wall of the threading block downwardly and rearwardly across the thread passage. It will be apparent that while the shuttle is in operation the running filling will pass between the guide pin 30 and guard 31.

15 When the filling carrier is ejected from the shuttle it moves bodily downwardly carrying the filling end with it. Fig. 5 shows the filling carrier and filling in the positions
20 they assume after the former has moved downwardly a very short distance. A comparison of this view with Fig. 4 discloses that when the filling carrier first starts downwardly, pulling the filling with it, the filling will contact with and run over the guide pin 30. The inclination of the guide pin will cause the filling to be moved toward the back wall of the shuttle, and thus removed from between the friction members, i. e. out from
25 under the top friction plate 20, as clearly shown in Fig. 5. Since the outgoing filling end is moved laterally of itself out of the tension and take-up device before the ejected filling carrier has moved any very substantial distance, the continued movement of the latter is unimpeded by any tension on the filling end, which is free to be withdrawn from the shuttle eye. This not only permits the filling carrier to fall out of the path of moving parts of the loom, but also prevents any likelihood of the filling breaking between the filling carrier and shuttle eye, which would be attended by the detrimental results previously mentioned.

45 The foregoing description of the preferred embodiment of my invention is by no means intended to limit the invention to the particular form disclosed. It is noted particularly that I believe I am the first to combine either a tension device or a slack take-up device in a loom shuttle with means for laterally removing the filling therefrom upon ejection of the filling carrier, and I desire to claim this combination broadly, regardless of the particular form of the elements of the combination.

50 Likewise, while the slack take-up device is designed primarily for use in the aforesaid combination it has points of superiority that render it desirable in and of itself, both as a take-up and as a plain first-pick tension. Furthermore, even though the device is thus used by itself it may be varied in detail without departing from the spirit of the invention.

I claim:

1. A shuttle for filling replenishing looms, comprising a shuttle body supporting an automatically ejected filling carrier, an automatically threading tension device carried by the said shuttle body, and an inclined guide pin positioned between the said tension device and the filling carrier and operable upon ejection of the filling carrier to engage and guide the outgoing filling end laterally out of the said tension device. 70

2. A shuttle for filling replenishing looms, comprising a shuttle body supporting an automatically ejected filling carrier, means carried by the said shuttle body for applying tension to the running filling, and an inclined guide positioned between the said tension means and the filling carrier and operable upon ejection of the filling carrier to guide the outgoing filling end laterally out of the influence of the said tension applying means. 80

3. A shuttle for filling replenishing looms, comprising a shuttle body supporting an automatically ejected filling carrier, a side delivery eye, a threading block between the filling carrier and the side eye, said threading block carrying a tension device comprised of upper and lower friction members yieldingly pressed together for applying tension to the running filling, and an inclined guide pin positioned between the said tension device and the filling carrier and operable upon ejection of the filling carrier to engage and guide the outgoing filling end laterally out from between the said tension members. 90

4. A shuttle for filling replenishing looms, comprising a shuttle body supporting an automatically ejected filling carrier, a take-up device, carried by the said shuttle body, capable of taking up a limited amount of slack in the running filling, and means operable upon ejection of the filling carrier to remove the outgoing filling end laterally from the said device. 100

5. A shuttle for filling replenishing looms, comprising a shuttle body supporting an automatically ejected filling carrier, a take-up device comprised of a pair of opposed friction members exerting a slip-grip on the running filling, said members being movably mounted in the shuttle body and yieldingly urged in a direction to take up slack in the running filling outside the shuttle, and means operable upon ejection of the filling carrier to remove the outgoing filling end laterally from between the said members. 110

6. A shuttle for filling replenishing looms, comprising a shuttle body supporting an automatically ejected filling carrier, a take-up device comprised of a pair of opposed friction members exerting a slip-grip on the running filling, said members being movably mounted in the shuttle body and yieldingly urged in a direction to take up slack in the running filling outside the shuttle, and means 120

operating automatically upon ejection of the filling carried to release the outgoing filling end from the said friction members.

7. An automatically threading loom shuttle comprising a shuttle body adapted to hold a filling carrier, a side delivery eye, and a take up device carried by the shuttle body between the filling supply and the side delivery eye for taking up slack in the filling outside the shuttle, the said take-up device including a pair of opposed friction members pivotally mounted for movement about an axis transverse to the running filling and adapted to exert a slip-grip upon the running filling, and means for yieldingly urging said members in a direction to effect said take-up action.

8. A loom shuttle having means for holding a filling carrier, a side delivery eye, and an automatically threading take-up device between the filling carrier and side delivery eye for taking up slack in the filling outside the shuttle, said take-up device being comprised of a friction member pivotally mounted for movement about an axis transverse to the running filling, a second friction member mounted for movement with the first said member and yieldingly urged toward the same for exerting a slip-grip upon the running filling, and means for yieldingly urging said members in a direction to effect said take-up action.

9. A loom shuttle having means for holding a filling carrier, a side delivery eye, and an automatically threading take-up device between the filling carrier and side delivery eye for taking up slack in the filling outside the shuttle, said take-up device being comprised of a horizontal friction plate pivotally mounted for movement about a vertical axis, a second friction plate mounted for movement with the first said plate and yieldingly urged toward the same for exerting a slip-grip upon the running filling, said plates being provided with guides for automatically guiding the filling therebetween, and means for yieldingly urging said plates in a direction to effect said take-up action.

10. A loom shuttle having means for holding a filling carrier, a side delivery eye, and an automatically threading take-up device between the filling carrier and side delivery eye for taking up slack in the filling outside the shuttle, said take up device being comprised of a friction member having a horizontal friction surface extending transversely of the running filling, and a second friction member positioned above and yieldingly urged toward the first said friction member for exerting a slip-grip upon the said filling, said members being yieldingly mounted for movement in a direction to effect said take-up action, and said friction members being provided with guides for automatically guiding the filling therebetween.

11. A loom shuttle having means for holding a filling carrier, a side delivery eye, and an automatically threading first-pick tension device between the filling carrier and side delivery eye for applying a tension to the running filling, said tension device being comprised of a horizontal plate over which the filling is adapted to run, a second horizontal plate positioned above said first mentioned plate, a spring for urging the said plates together, guides extending upwardly from the forward edge of said first plate, and a guide on said second plate presenting a downwardly and rearwardly inclined guide surface cooperating with said upwardly extending guides to automatically guide the filling to a position between said plates.

12. A loom shuttle having means for holding a filling carrier, a side delivery eye, and an automatically threading first-pick tension device between the filling carrier and side delivery eye for applying a tension to the running filling, said tension device being comprised of a flanged friction plate, a second friction plate cooperating with the first said plate to grip the filling therebetween, the said second plate being provided with a flange extending parallel to but spaced from the flange on said first plate, a rotatable pin having a nut threaded thereon, the nut being engaged by said flanges and thereby held against rotation, and a compression spring positioned between said nut and one of the said plates for yieldingly urging the plates together, rotation of the pin serving to move the nut axially thereon to thereby adjust the force exerted by the spring.

13. A loom shuttle having means for holding a filling carrier, a side delivery eye, and an automatically threading first-pick tension device between the filling carrier and side delivery eye for applying a tension to the running filling, said tension being comprised of a horizontal, apertured plate, a second horizontal plate positioned above and parallel to said first mentioned plate, a spring for urging said plates together, guides extending upwardly from the forward edge of said first plate, on opposite sides of the aperture therein, and a guide on said second plate presenting a downwardly and forwardly inclined guide surface cooperating with said upwardly extending guides to automatically guide the filling between the said plates and down through the said aperture.

EDWARD ROSS.
